DISPLAY CONTAINER FOR LAMP BULBS

John Robert Bassler, Newark, N. J., assignor to
Hudson Lamp Company, Arlington, N. J., a
corporation of New Jersey

Application November 19, 1952, Serial No. 22,373

Term of patent 7 years

(Cl. D58—13)

To all whom it may concern:

Be it known that I, John Robert Bassler, a citizen of the United States, residing at Newark, county of Essex, State of New Jersey, have invented a new, original, and ornamental Design for a Display Container for Lamp Bulbs, of which the following is a specification, reference being had to the accompanying drawing, forming a part thereof.

In said drawing:

Fig. 1 is a perspective view of a display container for lamp bulbs, showing my new design;

Fig. 2 is a bottom plan view thereof, drawn on a reduced scale; and

Fig. 3 is a vertical cross-section thereof, taken

on line 3—3 in Fig. 1, and drawn on a reduced scale.

I claim:

The ornamental design for a display container for lamp bulbs, as shown.

JOHN ROBERT BASSLER.
